ABSTRACT

A method of applying stones to sheet material by use of a translucent paper sheet with adhesive on one side and a pre-printed design on the reverse side, a protective sheet for the adhesive side which is removed to expose the pre-printed design, placing a series of prong settings upon the adhesive side over the printed design with the prongs in upward position, placing a sheet of material upon the prongs, pressing said material down with a sponge-like material so that the prongs pass through said material, placing stones within the prongs of said settings, bending the prongs to fasten the stones within the settings and removing the paper sheet from the material.

METHOD OF APPLYING STONES TO SHEET MATERIAL

This invention relates to a method of applying stones to sheet material.

More specifically, this invention is for a method of applying rhinestones to fabric in different designs by setting such rhinestones within metal prong settings or units and closing the prongs of such settings against the rhinestones thus securing the stones within the prong settings.

Heretofore, if a person desired to apply rhinestones to a fabric in a decorative design, such person would trace a design upon the fabric with pencil or a tailor's chalk, or other line marking device which may later be removed, then push the prongs of a prong setting along the traced lines through the fabric from the reverse side so that the prongs come through the right or face side of the fabric, then place a stone within the prongs of each prong setting and bend the prongs against the stone, either by hand or with a metal edge or tool, thus fastening the stone within the prong setting. The person places such prong settings along the lines of the design, spaced apart any desired distance until the entire design is covered. The person then places a stone within each prong setting and bends the prongs against the facets of the stone as soon as the prongs of each prong setting is in position, or such person may prefer to place all the prong settings through the fabric along the lines of the design and then place a stone within the prongs of each prong setting and then bend the prongs against each stone as it is in position. This is a long and tedious process and is not conducive to applying rhinestones to enhance the appearance of the fabric of a garment.

Furthermore, many persons do not have the artistic ability to create new, interesting and professional looking designs with rhinestones. Thus, the result obtained in the finished fabric, or garment made from such fabric, is amateurish and not a thing of beauty.

I have created a new and novel method of applying rhinestones to fabric inexpensively, rapidly, and with little effort.

As part of my method, I have created many beautiful and artistic designs for the application of rhinestones to fabric which may be used by any lay or inexperienced person, young or old, to enhance the appearance of many articles, such as blouses, pants, dresses, coats, suits, wall hangings, and similar articles.

For a fuller description of the nature and objects of my method, reference is had to the following detailed description in connection with the accompanying drawings, in which:

FIG. 1 is an enlarged cross-sectional view of a thin sheet of translucent paper with adhesive on one side covered with a sheet of protective paper.

FIG. 2 is a plan view of the thin sheet of paper with the protective paper removed exposing the adhesive and showing a flower design printed on the reverse side of the paper sheet.

FIG. 3 is an enlarged cross-sectional view of the thin sheet of paper shown in FIG. 1 with prong settings placed upon the adhesive layer which has the prongs of the settings passing through a fabric and stones placed within the prongs of the settings, one set of prongs shown in open position and the other set shown in closed position.

FIG. 4 is a top view of a rhinestone.

FIG. 5 is a side view of the stone shown in FIG. 4.

FIG. 6 is a cross-sectional view of a tool used to bend the prongs inwardly against the side facets of the stone.

FIG. 7 is a perspective view of a prong setting.

5 Referring to the drawing, numeral 10 represents a thin sheet of translucent paper of any desired dimension which has a thin film of non-drying tacky substantially transparent gum or adhesive 11 on the face side 12 thereof (like the well-known gummed paper tape) 10 and has a printed design 13 on the reverse side 14 thereof. As an example, I have shown a simple form of flower design. The design 13 is in the form of a spaced series of small letters 15, such as R, Y, G, etc. representing the colors red, yellow, green, etc. These letters 15 are visible on the face side 12 of the translucent gummed paper 10. The letters 15 designate the colors of the stones to be placed within the prongs 18 of the prong settings 17, as will be hereinafter described. A thin sheet of paper 16 preferably a waxed paper, of 20 about the same size as sheet 10, is applied to the film of non-drying adhesive 11 of the gummed paper 10 as a protective covering.

When a person desires to apply the flower design 13 to a piece of fabric, the pre-printed paper sheet 10 is 25 layed with the reverse side 14 upon a flat surface. Reverse side 14 may have a non-drying adhesive border, or a series of non-drying adhesive strips, covered by a protective waxed paper. By removing the protective waxed paper from reverse side 14, paper 10 30 may be firmly fixed to the flat surface to which it is applied so that it will not shift when the prong settings 17 are applied. The protective sheet 16 is then peeled from the gummed paper 10 exposing the series of spaced letters 15 seen through the gummed paper surface 11. The person then places a series of pre-colored prong settings 17 by hand upon the gummed side of paper 10 with the prongs 18 facing upwards. The settings 17 generally have four prongs 18; however, set- 35

40 tings with less or more prongs may be used. The flat circular surface 19 of the setting 17 adheres to the gummed surface 11 and remains in fixed position thereon. The settings are pre-colored by tinting with a single color, such as red, yellow, green, etc., on the prongs 18, or a single prong of the group of prongs 18
45 may be colored with a single color by any known method. The letters 15 of design 13 indicates the color of the setting 17 which is placed upon gummed side of paper 10 over the indicated letter. After all the colored settings 17 have been placed on the gummed side of paper 10 over the color indicated letters 15 of the entire design, a piece of fabric 20 to which the design is to be applied is placed with its reverse side upon the points 21 of prongs 18 in the desired position. The fabric 20 is then pressed down with a dry flat sponge, such
50 as a synthetic sponge which is well-known, so that all the prongs 18 pass through the fabric 20.

60 A colored rhinestone 22, having inwardly inclined facets 23, of the color indicated by the color or the prong, or prongs, is then placed within the group of prongs 18 of each setting 17. When all the stones 22 have been placed within the prongs of each setting, a tool 24, I have designed, is used to press the prongs 18 angularly against the inwardly inclined facets 23 of stones 22, thus fixing each stone in a non-movable position within the prongs of each setting 17. Tool 24 has a handle 25 and a concave hollow circular terminal 26. 65 A single downward pressure upon the points 21 of

prongs 18 with the hollow terminal 26 of tool 24 will bend all the prongs 18 inwardly against the inclined facets 23 of stones 22. The tool 24 is easily and rapidly used on the prongs of each setting 17 to firmly fix each stone within the setting.

When all the stones have been firmly set, the sheet 10 is separated from the fabric 20 and may be discarded or used again, if desired.

While I have shown a single design in FIG. 2, any number of different pre-printed designs may be used of any desired dimensions. Designs employing single or many different colored stones may be employed using my method. Also, gummed paper sheets without pre-printed designs may also be used and the person may mark their own design by line or color upon the back of the paper sheet 10 and use my method for applying the rhinestones to the fabric.

An alternative method of preparing the pre-printed design upon sheet or paper 10 is to print the indicia of the design upon the face side 12 of paper 10 before applying the substantially transparent adhesive 11 to the surface 12 of the paper 10. In this instance, paper 10 need not be translucent but may be opaque. The printed design can be seen through the transparent adhesive so that the person applying the prong settings 17 in the manner hereinbefore stated can readily follow the design and follow the method hereinbefore mentioned.

What is claimed is:

1. A method of applying stones to sheet material comprising
  - a. a sheet of translucent paper having substantially transparent adhesive on one side,
  - b. a pre-printed design on the reverse side thereof,
  - c. a removable protective sheet covering the adhesive side,
  - d. peeling said protective sheet from the adhesive exposing the design on the reverse side of said paper sheet,
  - e. placing a series of prong settings upon the adhesive side over the pre-printed design with the prongs in upward position,
  - f. placing a sheet of material upon the prongs of the settings,
  - g. pressing said material down with a sponge-like material so that the prongs pass through said material,
  - h. placing stones having inwardly inclined side facets within the upstanding prongs of said settings,
  - i. bending the prongs of said settings inwardly against the side facets of said stones to fix each stone within its setting,
  - j. then removing said sheet of translucent paper from said material.
2. The method set forth in claim 1 wherein the pre-printed design consists of indicia indicating the colors of the stones to be applied to said sheet material.
3. The method set forth in claim 2 wherein the set-

tings are colored to indicate the colors of the stones to be inserted in said settings for application to said sheet material.

4. The method set forth in claim 2 wherein at least one prong of each setting is colored to indicate the color of the stone to be inserted in said setting for application to said sheet material.

5. The method set forth in claim 2 wherein said indicia is a series of letters of the alphabet, each letter indicating the color of the stone to be set within each setting.

6. The method set forth in claim 1 wherein said sheet material is fabric.

7. The method set forth in claim 1 wherein said stones are rhinestones.

8. The method set forth in claim 1 wherein the inwardly bending of said prongs against the side facets of said stones is accomplished with a tool having a handle and a hollow terminal.

9. The method set forth in claim 1 wherein the reverse side of said translucent paper sheet has areas of non-drying adhesive thereon covered with a peelable protective sheet which is removed when placing said translucent paper sheet on a flat surface to prevent its moving when applying the prong settings.

10. A method of applying stones to sheet material comprising

- a. a sheet of paper having a pre-printed design on one side,
- b. a substantially transparent tacky adhesive covering said one side and said pre-printed design,
- c. a removable protective sheet covering said adhesive side,
- d. peeling said protective sheet from said adhesive exposing said pre-printed design,
- e. placing a series of prong settings upon said adhesive side over said pre-printed design with the prongs of said settings in upward position,
- f. placing a sheet of material upon the prongs of said settings,
- g. pressing said material down upon said prongs with a sponge-like material so that said prongs pass through said material,
- h. placing stones within the upstanding prongs of said settings,
- i. bending said prongs of said settings inwardly against the sides of said stones to fix each stone within its setting,
- j. then removing said sheet of adhesive paper from said material.

11. The method set forth in claim 10 wherein the reverse side of said paper sheet has areas of non-drying adhesive thereon covered with a peelable protective sheet which is removed when said paper sheet is positioned upon a flat surface to prevent its moving when applying said prong settings.
